UNITED STATES PATENT OFFICE.

ALBERT E. PAGE, OF BROOKLYN, NEW YORK, ASSIGNOR TO SCOTT & WILLIAMS, INCORPORATED, OF NEW YORK, N. Y., A CORPORATION OF MASSACHUSETTS.

KNITTING ON TRANSFERRED FABRIC SECTIONS.

Application filed May 19, 1928. Serial No. 279,014.

- This invention relates to machine knitting of the kind resorted to for the manufacture of knit articles including a part made by one kind of operation or on one kind of machine, 5 and further made by another kind of operation, or on another machine to which the product of the first operation is applied or transferred, so that further knitting begins where the first knitting ends.
- 10 For example, it is customary to knit such articles as children's or men's socks or half-hose and certain kinds of gloves with a ribbed or other elastic or specially patterned section, and to continue or complete the article in plain knitting; for specific instances, to knit 15 the leg, ankle and foot of a stocking on a circular heel and toe fashioning machine in integral continuation of a tubular ribbed top having a welt; or to knit a circular machine 20 foot in continuation of the terminal instep course and lateral heel-flap selvages of a straight-machine flat-fashioned blank.
- The most convenient ways to continue 25 making any knit article partly completed on one machine on another machine include the use of some kind of transfer device by which the terminal loops, selvage loops or other structure of the first-made part of the article may be impaled in order on the needles of the 30 second machine. If the machine resorted to for the second stage of knitting is a circular machine, for example, the transfer device may be a cylindrical or conical carrier having quills to fit over the leveled needles of the 35 circular machine, and the actual transfer comprises causing the needles to penetrate loops held open by the quills, and engage the loops in their hooks; and subsequent removal of the transfer device.
- 40 In order to make sure that knitting can safely start on transferred fabric, however, it is necessary that so much of every needle of the second machine as must have passed through any previous loop before taking new 45 yarn shall have reached this relation to the loops of the transferred fabric section before knitting can begin. If the second machine is a spring-needle machine, for example, the points of the needle-beards must clear 50 through the transferred loops before feeding new yarn into their hooks, and the transferred fabric must be so placed as to permit the beards to be pressed before retraction; and if the second machine is a latch-needle 55 machine, it is desirable to make sure that the transferred fabric will not be lifted by the advance of a needle requiring to have the tip of its open latch cleared of any previous loop before the next subsequent retraction with new yarn. As heretofore performed, the 60 transfer operation generally implies a hand adjustment of the transferred fabric before beginning to knit to a low position on the receiving needles, and on some kinds of machine it is difficult to reach the transferred 65 fabric to do this by hand. The transfer implements themselves are not able to complete positioning of the loops operatively on the shanks of receiving needles. This is especially the case when the receiving machines 70 have the ordinary kind of web-holder mechanism, in which all of the web-holders are normally too far in to permit transferred loops to reach a position under their hold-down hooks; or when for any reason it is desirable 75 to transfer to needles in a retracted or intermediate position.
- One object of this invention is to provide 80 the receiving machine for use in such situations with automatic means for adjusting a transferred fabric section on its needles and in relation to its web-holders prior to a knitting motion of each needle in such a way as to insure an operative position of the transferred fabric in relation to the needle at its 85 first and subsequent operative movements. Another object of the invention is to provide 90 a device for this purpose capable of cooperation with any kind of transferred fabric section and any kind of web-holder device; and a further object is to permit transfers to 95 needles while the needles are in a low position with respect to their web-holders, and therefore more accurately spaced, without failure to knit the first course correctly.
- In the accompanying drawings, which illustrate a specific instance only,
- Fig. 1 is a vertical diametrical section through the upper part of a circular latch needle knitting machine showing the position 100 of parts just prior to initiation of knitting;
- Fig. 2 is a corresponding detail in plan showing the interior yarn guide and clamp, and fabric positioning devices;
- Fig. 3 is an under plan of a web-holder cam-cap explanatory of the motions of web-holders; and
- Fig. 4 is a left side elevation of a detail of Fig. 2.

The receiving knitting machine, referring 110

to Fig. 1, may have any kind of needle cylinder or other carrier 1, grooved to guide needles *n*, and may be provided with any kind of web-holder bed 2 for any usual form of web-holders *w* worked in and out between the needles, so that there is a wave *x*, Fig. 2, of withdrawal of the hold-down hook parts *w'* of the web-holders from a point following a rise or advance in the needles to take yarn, 10 to a point following the substantial retraction to knit of the needles and at or immediately following their most retracted position to knit, as usual. These motions of the web-holders are functions of cams in the machine of the Scott & Williams type shown, 15 carried on a web-holder cam-cap 3, Fig. 3, and including a withdrawing cam *3^a* and advancing cam slopes *3^b*. Whatever the direction of relative motion of the parts, for example the cylinder 1 and bed 2, in respect to the cams, not shown, for operating the needles, and the cams on cap 3 for working the web-holders, the cap 3 is restrained from following by contact of one or the other of 20 stops *3^c* against a fixed part 40, which may be a post fixing the closed or operative position of a latch-ring or yarn guide carrying element 5, horizontally pivoted on a fixed part to the left of Fig. 1, not shown, all as 25 usual. This results in a web-holder wave of retraction, at *x*, Fig. 2, for example, long enough in relation to the lost motion between *3^c* and 40 always to include a substantial angular space, for example corresponding to 30 a part of the width of and opposite to a yarn-feeding throat 4 formed in the ring 5, which accommodates yarn-feeding yarn fingers, one of which is shown at 6 in operative position. The end of the yarn *y* supplied by finger 6 may be guided or clamped as usual on the upper face of an internal platform 7, slightly above the plane of intersection of the upper arms of the web-holders *w* and the surface defined by the needles, in 35 which plane the fabric and new yarn is supported by the web-holders, by a receiving guide 8 and clamp 9 pivoted at 10 on an overhung bracket 12 on latch ring 5. Bracket 12 may also support a severing device 11 for 40 yarn *y*, and on the under face of the platform 7 projections 13 and 16 may as usual be relied upon to guide fabric, especially heels and toes, downward into the hollow needle cylinder.

45 When a transferred fabric section *f*, Fig. 1, is applied to the needles *n*, the pivoted latch ring 5 having been lifted out of the way, it is customary first to level the needles *n* by removing a cam operating them during a revolution of their carrier, and then beginning knitting movement of the needles and feeding yarn prior to the first needle moved to knit, but whether or not this is done, all of the web-holders *w* except those in the withdrawal wave at *x* stand with their hold-down

hooks between the needles, as shown at the right in Fig. 1. It is not desirable to rely on motion of the needles to position the fabric in proper relation to the web-holders, and the transfer device can not depress loops impaled on the shanks of the needles below the plane of the hold-down hooks *w'*. In large-diameter machines in which there are no devices interiorly of the needle cylinder it is possible for the operator to reach a hand 70 from below to pull down on the fabric. Otherwise, weights have to be used before starting to knit to pull down the impaled edge to the position shown in Fig. 1. This is an uncertain operation, and the weights 75 required often result in damaged fabric.

Whether the machine is required to knit on the first part of its motion after the latch ring is returned to operative position, or whether it is provided not to begin operation of the needles to knit until after rotation has begun, this invention provides an instrument 20 to act on the transferred fabric at the beginning of rotary motion progressively to depress on the needles the fabric 80 transferred below the level of the hold-down hooks of the web-holders, while the hooks of the web-holders are retracted, as at *x*, so that their first insertion thereafter is operative to thrust a hold-down hook over the 85 transferred edge of the transferred fabric.

The instrument 20 may be of any suitable form to perform this operation. As shown, it includes a cam 21, Fig. 4, held near the backs of the needles opposite wave *x*, and preferably made as a rounded down-turned end portion of a horizontally placed arm fastened on platform 7, as by screws at 22 entering holes in a block 23, which may be the mounted end of the receiving guide 8 already on the machine. The uppermost normal extent of the instrument 20 is preferably not high enough to prevent delivery of yarn by a finger 6 below the hook ends of needles *n*, either at transferring or at normal knitting position of the needles. The normal clearance of the operating cam end 21 of the instrument above the upper edges of the inward arms of the web-holders *w* is sufficient only to accommodate the expected thickness of the transferred fabric *f*. It will be apparent that, since this instrument is always within the wave *x*, the withdrawn web-holders permit the edge of fabric *f* to be moved down the needle shanks to the correct position against the resistance of such parts of the transferred edge as do not readily slide onto the thicker parts of the needle, such as the cheeks at their latch pivots, without failure and without breakage.

What I claim is:

1. In a knitting machine for knitting on transferred fabric section having needles and web-holders, and means for retracting and for advancing the web-holders, means oper-

ating in relation to the retracting means for the web-holders mounted on the machine in relation to said web-holder retracting and advancing means and acting on a transferred fabric section during knitting progressively to move the said fabric section on the needles into operative position in respect to subsequently advanced web-holders.

2. In a circular knitting machine for knitting on transferred fabric section having needles and web-holders, and an internal yarn guiding device mounted above and near the plane of intersection of the needles and the fabric-supporting edges of the web-holders, and means for retracting and for advancing the web-holders, means mounted on the internal yarn guiding device in relation to the retracting means for the web-holders acting on a transferred fabric section progressively to move the said fabric section on the needles into operative position at said plane of intersection in respect to subsequently advanced web-holders.

3. In a knitting machine in combination with needles, web-holders having hold-down hooks, means for advancing the web-holders and for retracting the web-holders in a wave, and a cam at the backs of the needles adapted to act progressively on transferred fabric near the backs of the needles and in respect to retracted web-holders to move said fabric on the needles into a plane under said hold-down hooks.

4. In a circular knitting machine in combination with needles, a removable support for yarn guides, web-holders having hold-down hooks, means for advancing the web-holders and for retracting the web-holders in a wave,

and a cam mounted on said removable support and operatively positioned at the backs of the needles and thereby adapted to act progressively on transferred fabric near the backs of the needles and in respect to retracted web-holders to move said fabric into a plane under said hold-down hooks.

5. In a knitting machine for knitting on transferred fabric sections, in combination with means for initiating knitting by forming a wave of motion in needles leveled for transfer and feeding yarn to said needles, web-holders, means to retract them at retracting needles, and means to advance them, cam means fixed in relation to said respective waves of motion adapted progressively to act on transferred fabric to move it into position for operative contact with web-holders prior to their advance.

6. In a circular knitting machine in combination with needles, yarn-feeding means including an internal yarn guide device mounted to be moved into and out of operative position, web-holders having hold-down hooks, means for advancing the web-holders and for retracting the web-holders in a wave, and a cam mounted on the internal yarn-guide device adapted when said device is operatively positioned to act at the backs of the needles and progressively on transferred fabric near the backs of the needles and in respect to retracted web-holders to move said fabric down on the needles into a plane under said hold-down hooks.

Signed by me at New York, New York, this 18th day of May, 1928.
